SPLASH GUARD FOR MOTOR VEHICLES

Robert Podall, Highland Park, Ill., assignor to Jeffrey-
Allan Industries, Inc., Chicago, Ill., a corporation of Illinois

Filed June 24, 1965, Ser. No. 85,893

Term of patent 14 years

(Cl. D14—6)

The drawing is a perspective view of a splash guard for motor vehicles embodying the design.

The side opposite that shown and claimed is substantially plain.

I claim:

The ornamental design for a splash guard for motor vehicles, as shown and described.
